UNITED STATES PATENT OFFICE.

HENRY L. CRUTTENDEN, OF NORTHFIELD, MINNESOTA.

DENTAL-CEMENT-INJECTING TUBE.

1,279,664.

Specification of Letters Patent. Patented Sept. 24, 1918.

Application filed December 15, 1917. Serial No. 207,238.

To all whom it may concern:

Be it known that I, HENRY L. CRUTTENDEN, a citizen of the United States, residing at Northfield, in the county of Rice and

5 State of Minnesota, have invented certain new and useful Improvements in Dental-Cement-Injecting Tubes; and I do hereby declare the following to be a full, clear, and exact description of the invention, such 10 as will enable others skilled in the art to which it appertains to make and use the same.

My present invention relates to dental cement injecting tubes of the general character 15 disclosed and claimed in my prior Patent #716,677, of date, December 23rd, 1902, and subsequent Patent #749,846, of date, January 19, 1904.

Particularly, the present invention is in 20 the nature of an improvement on the tube disclosed and claimed in my said Patent 749,846. The said tube has been put on the market in large quantities and has hitherto been made of uncolored gelatin, and hence, 25 almost perfectly transparent. The transparency is desirable to enable the user to determine whether or not the tube is completely filled with cement and free from air holes. However, this nearly perfect transparency 30 has the disadvantage that when laid upon objects of different color, they are not readily visible, because they partake of the color, or rather the color of the supporting object will be shown through the tubes, which 35 has the effect of making the tubes hard to quickly locate. Inasmuch as a dentist must work rapidly in filling teeth, it is important that the tubes be always distinctly visible, so that no time will be lost in picking one 40 up when it is required. I have found that by coloring the large or butt end portion only of the tubes, leaving the main body portion thereof in clear transparent gelatin, all of the good advantages of the previous 45 transparent tube is retained and the further advantage of greater visual prominence is obtained. I also provide a novel material for coloring the butt end portions of the tubes in quantities.

50 In the accompanying drawings which illustrate the invention, like characters indicate like parts throughout the several views.

Referring to the drawings,

Figure 1 is a side elevation showing a com-

plete tube with a colored butt end and transparent body;

Fig. 2 shows a stack of tubes threaded on a supporting needle; and

Fig. 3 is a plan view showing a tool which is preferably used in coloring the butt ends of the tubes.

The transparent gelatin tube is indicated by the character *a* and its colored butt end portion by the character *b*.

The numeral 4 indicates a needle, such as 65 a knitting needle, which is preferably set in an upright position and rigidly secured at its lower end to a suitable support 5.

The clear or transparent gelatin tubes *a* are telescoped together and, in a stack, inserted onto the needle 4. This operation serves also to open up the ends of the nipple portions of the tubes. By reference to Fig. 2, it will be noted that the tubes of the stack have their ends exposed about $\frac{1}{4}$ inch, the 70 total length of the tool which is just the 75 desired extent to which the tubes should be colored.

The coloring may be produced in different ways, but preferably, is accomplished by 80 the tool shown in Fig. 3. This tool comprises a handle 6 having an annular clamping head 7, which latter holds an annular coloring pad 8 of felt or other suitable material. The hole in the pad 8 is of such size 85 that the pad can be slipped down over the stack of tubes in close frictional contact therewith. Hence, when this pad 8 is saturated with a suitable coloring material and is forced down over the stack of telescoped 90 tubes, it will color the exposed butt end portions thereof, all with one operation. Then when the tubes are separated, they will appear as in Fig. 1. Preferably the extreme upper end tube of the stack will be used over 95 again as a starting tube, because, since its whole external surface is exposed, it will be colored throughout the greater portion of its length.

Any suitable coloring material may be 100 used, but preferably, I would use a non-poisonous vegetable coloring matter, such as used in making candy and confections. In practice, I have used a red or carmine color, but any other shade or color may be used. 105 Obviously, by the above described arrangement, the coloring matter is placed entirely on the exterior of the tube leaving the in-

terior of the tube clean and free therefrom. This is important, inasmuch as coloring matter on the interior of the tube may introduce impurities into the cement which would be, thereby, carried into the tooth cavity.

What I claim is:

1. A collapsible dental cement injecting tube having a large open end and an attenuated discharge nipple at its other end, said tube being of collapsible transparent material but having a colored end portion.
2. The process of coloring dental cement injecting tubes of the character described,

which consists in telescoping the same with butt end portions exposed, and in thereafter 15 coloring the said exposed butt ends, thereby forming colored bands around the butt ends of said tubes and leaving the main body portions thereof uncolored.

In testimony whereof I affix my signature 20 in presence of two witnesses.

HENRY L. CRUTTENDEN.
